CLAIM

The ornamental design for a polishing machine for metal, as shown and described.

DESCRIPTION

1.1 is a first perspective view of the polishing machine for metal;

1.2 is a second perspective view thereof;

1.3 is a third perspective view thereof;

1.4 is a front view thereof;

1.5 is a back view thereof;

1.6 is a left view thereof;

1.7 is a right view thereof;

1.8 is a top view thereof.

The reflections shown in reproductions 1.1, 1.2, 1.3 and 1.8 are disclaimed.

The broken lines shown in the drawings and the elements contained within the faded regions they define, depict por-

(Continued)

tions of the polishing machine for metal in which the design is embodied that form no part of the claimed design.

1 Claim, 8 Drawing Sheets
